(57) **CLAIM**

The ornamental design for a beanie with hair outlet, as shown and described.

DESCRIPTION

FIG. 1 is a rear perspective view of a first embodiment of a beanie with hair outlet;

FIG. 2 is a rear view thereof;

FIG. 3 is a front view thereof;

FIG. 4 is a first side view thereof;

FIG. 5 is a second side view thereof;

FIG. 6 is a top view thereof;

FIG. 7 is a bottom view thereof;

FIG. 8 is a rear perspective view of a second embodiment of a beanie with hair outlet;

FIG. 9 is a rear view thereof;

FIG. 10 is a front view thereof;

FIG. 11 is a first side view thereof;

FIG. 12 is a second side view thereof;

FIG. 13 is a top view thereof; and,

FIG. 14 is a bottom view thereof.

The even length broken lines define portions of the beanie with hair outlet that form no part of the claimed design. The dash-dot-dash broken lines define the bounds of the claimed design and form no part of the claimed design. The areas within the dash-dot-dash broken lines form no part of the claimed design.
